UNITED STATES PATENT OFFICE.

RICHARD H. WELLES, OF KENOSHA, WISCONSIN, ASSIGNOR TO THE BADGER BRASS MFG. CO., OF KENOSHA, WISCONSIN, A CORPORATION OF WISCONSIN.

HEADLIGHT.

No. 922,826.

Specification of Letters Patent.

Patented May 25, 1909.

Application filed September 19, 1907. Serial No. 393,624.

To all whom it may concern:

Be it known that I, RICHARD H. WELLES, a citizen of the United States, residing at Kenosha, in the county of Kenosha and State 5 of Wisconsin, have invented certain new and useful Improvements in Headlights, of which the following is a specification.

This invention relates to improvements in headlights and refers more specifically to improvements in headlights of that type which are employed for lighting the roadway in advance of vehicles or boats; the particular embodiment shown herein being suitable for use in connection with automobiles.

15 The salient object of the present invention is to provide in conjunction with a headlight an auxiliary mechanism whereby the normal light may be modified and so changed as to eliminate the glare due to the beam of parallel or approximately parallel rays.

Subsidiary objects of the invention are to provide in conjunction with the usual mechanism of a headlight a device performing the combined functions of a shutter and a diffusing reflector, and which may be temporarily thrown into operation and withdrawn from operative position at will; to provide such a mechanism of simple, inexpensive and effective construction which returns by gravity 25 to its normal or inoperative position and may be manually thrown into operative position at will, and in general to provide a simple and improved mechanism of the character referred to.

35 The invention will be readily understood from the following description, reference being had to the accompanying drawings, in which—

Figure 1 is a vertical axial sectional view 40 of a headlight equipped with my invention; Fig. 2 is a cross sectional view taken on line 2—2 of Fig. 1 and looking in the direction of the arrows.

In headlights as now commonly organized 45 for use in connection with automobiles, locomotives, boats, etc., both the light which emanates directly from the front side of the burner and that which emanates from the rear side thereof is utilized; the latter being 50 reflected, and often refracted, by a suitable reflector or combined reflector and refractor located in rear of the light. The present invention has to do with headlights of this character, and, as will hereinafter appear, 55 is capable of embodiment in a construction

which uses a reflector devoid of refracting means, or, as shown in the preferred embodiment illustrated, may be utilized with a refracting reflector.

Referring to the drawings, 1 designates as 60 a whole the headlight casing or barrel, which is shown as consisting of a cylindric side wall member 2, a flaring front rim 3 and an outwardly convex rear end wall 4. Seated in the rear end of the casing is a reflector 5 of 65 that type known as a Mangan mirror; this reflector being of well-known construction and serving to not only reflect the rays but to modify their direction so that the rays emanating from a focal point are reflected 70 and at the same time brought into parallelism with each other.

For the protection of the interior parts of the headlight, the front end of the casing is 75 closed by a plain glass or crystal 6, which, as shown, is made of uniform thickness throughout and therefore does not substantially vary the direction of the rays passing therethrough. Preferably said crystal is made sectional, as seen clearly in Fig. 2. 80

7 designates the burning nozzle, which as usual enters through the lower side of the headlight casing, rises vertically therein and terminates in a burner tip located just below the focal point 8 of the headlight, so that the 85 burning jet will occupy this focal position. The burner in this instance is an acetylene gas burner, and a gas supply pipe 9 connects with the lower end of the burner nozzle at a point outside of the casing. 90

Describing now the dimming mechanism, 10 designates a rock-shaft journaled to extend through a suitable cap-like bearing housing 11 mounted upon the exterior of the casing, conveniently at a point somewhat 95 below the horizontal diameter of the casing and so as to extend parallel with the axis of the latter. Conveniently said shaft is made rectangular in cross section and has mounted thereon a pair of cylindric hubs 12 which 100 are journaled between the housing cap 11 and the opposed side wall of the casing. Between the hubs 12 is mounted upon the shaft 10 an arm 13, which carries at its longer free end a circular concave reflector 105 14. This reflector is of such diameter that when sustained in axial alignment of the focal point 8 of the headlight it intercepts those rays which would otherwise impinge upon the mirror 5 and reflects them out 110

through the front light in a pencil or beam, the rays of which are only moderately divergent and so that this beam of reflected light is considerably more concentrated than the beam of direct light passing out through the front glass. That is to say, the direct light is diffused over the angle comprised between the extreme margins of the front glass while the reflected light is concentrated to a considerably less angle, with the result that the central field of the headlight is quite intensely illuminated yet without producing such a beam as to produce a glaring effect, while the exterior portions of the field are illuminated sufficiently for practical purposes. The arm 13 is provided with a crank arm extension 15, to which is attached an operating cable 16 which extends laterally to and is trained through a guide 17 so located as to cause the cable to draw at right angles to the shaft 10. In the lower side of the casing is formed a pocket 18 which, when the arm 13 is in lowered position, receives the major part of the reflector 14. This pocket is conveniently applied and attached to the exterior of the headlight in register with a slot opening 19 through the lower side of the latter, which admits the reflector to the pocket.

30 The operation of the apparatus constructed as described will be entirely obvious from the foregoing description. Normally the reflector occupies its position in the pocket and the light emanates from the focal point, 35 part of it passing directly through the front glass, and that which emanates rearwardly being reflected and refracted by the Mangan mirror into a beam of parallel rays. This latter beam gives the usual searchlight effect 40 while the direct light furnishes the side illumination.

When it is desired to eliminate the glaring effect of the searchlight beam, the operator simply draws on the cable 16 and raises the 45 reflector 14 into operative position. The back light is thus cut off from the Mangan mirror and reflected as a beam of moderate divergence which does not produce the glaring effect in the eyes of approaching 50 servers.

It will be obvious that the details of construction and arrangement may be some-

what modified without in any sense departing from the spirit of the invention.

I claim as my invention:

1. In a headlight, the combination with a suitable casing, of a burner located intermediate the length of said casing, a main reflector in the rear portion of the casing constructed to reflect the rays from a focal point in approximate parallelism, and a movable reflector adapted to be interposed between the burner and main reflector to modify the reflected beam of light. 55

2. In a headlight, the combination with a suitable casing, of a burner located intermediate the length of said casing, a main reflector in the rear portion of the casing constructed to reflect the rays from a focal point in approximate parallelism, and a reflector movable into and out the field of light between the burner and main reflector for modifying the reflected beam of light. 60

3. In a headlight, the combination with a suitable casing having an approximately 75 cylindric interior, of a burner located axially of, and intermediate the, length of the casing, a Mangan mirror arranged in rear of the burner, and a concave reflector shiftably mounted to move into and out of a position 80 between said mirror and burner.

4. In a headlight, the combination with a casing, of a burner located intermediate the length of the casing and two reflectors arranged in rear of the burner, one of said reflectors being movable into and out of position to screen the other from the burner. 85

5. In a headlight, a casing, a burner, and means arranged between the rear of said casing and said burner for alternatively reflecting the rearwardly extending rays of light as a parallel-ray beam or as a divergent-ray beam. 90

6. In a headlight, a casing, a burner, and manually controlled means arranged between the rear of said casing and said burner for alternatively reflecting the rearwardly extending rays of light as a parallel-ray beam or as a divergent-ray beam. 95

RICHARD H. WELLES.
